MEANS FOR PROVIDING VARIABLE
CAPACITY HIGHWAYS

Otto K. Jelinek, Chicago, Ill.

Application August 3, 1940, Serial No. 350,962

11 Claims. (Cl. 94—1)

This invention relates to improvements in means for providing variable capacity or convertible highways and is a further development of the construction shown in my Patent 2,182,697 issued December 5, 1939.

The general object of the invention is to provide improved power-actuated means and accessories for raising and lowering the curb or curbs which define the traffic lanes.

Other objects are: to improve the construction of the curb itself; to provide fluid pressure actuated mechanism of compact form which may be located in the trough in which the curb is mounted; to provide vertical power actuated jacks at intervals in the channel or trough for raising the curb section, each curb section being lifted by two or more jacks; to provide means for so connecting the adjacent ends of curb sections as to provide a flexible or universal joint which in turn is directly supported by one of the jacks, whereby each of said sections is supported on said jacks at opposite ends thereof; to provide metal castings or wear plates in the side walls of the concrete trough to guide the curb sections in their up and down movement independently of the jacks, and to enable said curb sections to resist side blows or lateral thrusts; to provide means for insuring downward movement of the curb sections when the fluid pressure is released, so that said sections will not be held in upper position by snow and ice in winter; to provide the curb sections with a layer of the same kind of paving material on the top thereof as is used in the main highway so as to avoid skidding; to provide an improved hollow vertically adjustable curb having a source of illumination inside the same and openings or transparent panels in the sides thereof so that the curb and the adjacent portions of the road, may be readily seen at night.

Various other objects and advantages will be apparent as the description proceeds.

In the accompanying drawings several embodiments of the invention are illustrated.

Fig. 1 is a plan view of part of a four, double-lane or eight-lane highway, showing the location of the vertically adjustable curbs;

Fig. 2 is a section, on a larger scale, on the line 2—2 thereof;

Fig. 3 is a top plan view of one section of steel curbing, without the upper layer of paving thereon;

Fig. 4 is a longitudinal, sectional elevation through one of the concrete lined troughs or

trenches showing a length of curb therein, with many details omitted;

Fig. 5 is a plan view of one of the wear castings;

Fig. 6 is a side elevation thereof;

Fig. 7 is a section on the line 7—7 of Fig. 5;

Fig. 8 is a section on the line 8—8 of Fig. 6;

Fig. 9 is an enlarged transverse section, somewhat simplified, through one of the trenches showing the curb in uppermost position;

Fig. 10 is another transverse section showing the curb in lowermost position and the compression springs extended;

Fig. 11 is a short section at right angles of Fig. 70;

Fig. 12 is a section showing the illuminating feature;

Fig. 13 is an elevation of a modified form of the invention;

Fig. 14 is a partial plan view of the flexible joint showing the structural details;

Fig. 15 is a section thereof on the line 15—15 of Fig. 14;

Fig. 16 is a view of the hydraulic jack of Fig. 13 in elevated position;

Fig. 17 is a sectional view of an illuminating cabinet;

Fig. 18 is a perspective view thereof;

Fig. 19 is a perspective view of a modified fitting apparatus;

Fig. 20 is a sectional elevation of a further lifting apparatus;

Fig. 21 is a similar view showing the curb elevated;

Fig. 22 is a diagram of another modification; and

Fig. 23 is a perspective view of an additional modification.

In Fig. 1 there is shown somewhat diagrammatically a top plan view of a highway having sufficient lanes for eight cars, side by side, but divided by curbs into four double lanes. The outside curbs 10, 10, are of the usual construction. The three intermediate curbs 11 are flush with the pavement part of the time, but each or all of them may be raised so that they will project sufficiently to constitute an effective barrier or curb, when required.

These curbs 11 and the trenches 12 or slots in the pavement in which they are confined, are shown somewhat diagrammatically in section, and on a larger scale, in Fig. 2.

Assuming that the traffic toward the business district of a city is mainly southbound, as during the morning rush hours, the three left hand

double lanes are made available for traffic, as shown in Fig. 2, i. e. the two left hand movable curbs are retained in lowermost position in the trenches or troughs, with their tops flush with the level of the pavement. The right hand one of the three curbs is shown as raised to its uppermost position, thus providing a double northbound lane and three southbound double lanes. In other words, two traffic lanes are provided for northbound vehicles and six are provided for southbound vehicles.

During the evening rush hours when the traffic is mainly in the opposite direction, the right hand movable curb is lowered and the left hand movable curb is raised, thus providing for six northbound traffic lanes and two southbound traffic lanes. At other times of the day the middle curb only may be raised, thus providing four northbound traffic lanes and four southbound traffic lanes.

In the commercial installation now described herein, the movable curbs are made preferably in twenty-five foot lengths and may have a width of about twenty inches and a vertical height of about sixteen inches and are commonly referred to as fins. One of these curb sections 13 is shown in Fig. 3. The said trenches 12 are made preferably of concrete, as shown in Figs. 2, 9 and 10.

Each curb length is supported on two hydraulic jacks 14, 14, which rest on suitable concrete foundations in the trenches and are spaced at regular intervals. Each length, as shown in section in Figs. 10 and 11, is made preferably with steel side plates 15 connected by a cross plate 16, welded thereto a few inches below the top, which provides an upper channel to be filled with concrete or other paving material similar to the main paving on the road. The lower sides of the plates 15 are reinforced by horizontal flanges 17 which may be welded thereto as shown, or may be rolled integrally therewith. The lower part of the curb has the form of a hollow box-like structure. Said curb is guided in its up and down movement by lugs 18, 18, as shown in Fig. 10, which lugs slide up and down against vertical guides provided by suitable brackets 19 imbedded in the concrete on each side.

A pair of vertical rods 20, 20, as shown also in Fig. 10, have their upper ends secured to the cross plate 16 and at their lower ends are turned outwardly and upwardly in the form of hooks to support the lower end of the helical spring 21, which in said figure are extended the maximum amount, with the upper end confined by the plate 22 which is secured to the upper end of the rod 23, the lower end of which is anchored in the concrete. When the power is applied to raise the curb in the manner hereinafter described, the curb, as it lifts, carries with it the rods 20, 20, which compress the springs 21 in each case until the curb reaches its uppermost position, shown in Fig. 9.

When the power is released, the springs elongate and lower it. Ordinarily the curb would lower of its own weight except when the curb becomes jammed or obstructed in uppermost position, due to ice forming in winter, or other obstructions. The main purpose of the springs is to overcome the initial resistance, after which the curb will sink of its own weight. Lateral braces or channel plates 24 are positioned transversely adjacent each jack and are welded in place as shown. Each brace 24 has a metal

extension of foot 25 secured to it which rests on a seat or stop 26 to limit the downward movement of the curb, i. e. the curb rests on said seat normally when in lowermost position, 5 in which position it supports the weight of automobiles running over it.

Each curb is raised preferably by two fluid pressure actuated jacks 14, as previously stated, one of the jacks being shown in section in Fig. 11. It comprises a cylinder 27 mounted on a suitable base, with a concrete or other footing 28 under it and it is provided with a hollow piston 29 in the form of a cylinder closed at the lower end. The hydraulic pressure, i. e. the fluid under pressure preferably in the form of oil, is pumped through suitable pipes to the cylinder and through the lower port 30, and as the piston is lifted it raises the short vertical shaft 31 which rests in the seat in the bottom thereof 20 and extends above the piston, being received in an inverted cup-shaped seat 32, welded or otherwise secured to the cross plate 16 of the curb. This provides a loose connection which permits operation of the curb despite slight irregularities 25 during the up and down movement.

Assuming that the roadway equipped with these curbs is several miles long, it is preferably operated as a number of separate divisions. Each division may have a separate pump station and distribution station to actuate any one or two or all three lines of curbing. Ordinarily, only one length of curbing is operated at a time but all the 25 foot lengths of curbing in a composite unit may be operated simultaneously. 30 For example, a length of curbing of 300 feet may first be raised a distance of a few inches, followed immediately by another similar length, as the first length continues to rise, and so on with other sections, giving a stepped arrangement. 35 Suitable switches at the control station start the train of movements. The lifting action may be said to be in the form of a wave action, the movement of the wave being about 20 M. P. H. or any other desired rate. The mechanism for accomplishing this progressive operation is similar to 40 that used in operating traffic signals so as to insure a certain rate per hour for the travel of the vehicles, hence said mechanism and the control system therefor is not described herein.

As shown in the top plan view, Fig. 3, there may be one or more hand hole covers 35 provided, which may be unscrewed to give access to the incandescent lamp 36 immediately beneath the same. In opposite sides of the curb are glass lenses 37 or bull's-eyes (see Fig. 12) so that when the curb is raised, it will be readily seen at night. The conductors 38 may extend throughout the length of each section with a flexible connection to the next unit to provide for up and down movement of adjacent sections.

A modified form of this feature is shown in Figs. 17, 18, in which the incandescent light and the lenses are mounted near the ends of the curb length as a unit 40, to be slid in from one side of the curb when the latter is in elevated position. The lenses 41 are mounted in opposite ends of the box-like structure, which latter has resilient circuit contacts 42 beneath the same, adapted to contact with circuit contacts 43 permanently mounted in the curb section. 50 When pushed into place the circuit is closed by said contacts. This eliminates the necessity of the hand hole covers.

Wear plates 45 are welded onto the sides of the curb at regular intervals of about five feet

to slide up and down on the wear castings 46 now described. (See Fig. 10.)

The castings 46, as shown in Figs. 5, 6, 7, 8, 9 and elsewhere, serve to reinforce the side walls of the trench and provide a metal facing for the slot through which the curb moves up and down. These castings may be about five feet long and are provided with intermediate, transverse arms 47 having enlarged heads to anchor in the concrete, and with transverse end plates 48 (see Figs. 5 and 8). These castings are bolted to the brackets 19 which provide a vertical abutment against which the lugs 18 slide to prevent longitudinal movement of the curb (see Figs. 3 and 10). In the form shown, there are five castings 46 for each curb section.

These castings not only serve to guide the up and down movement of the curbs, making it possible to provide a loose connection between the elevating mechanism and the under part of the jacks, but said castings enable the curb to resist the heavy side thrusts received from time to time when automobiles accidentally run against the side of the curb or where cars are thrown against the curb in automobile accidents.

Another form of curb is shown in simplified form in Fig. 13 in which the jacks are connected with adjacent ends of curb lengths instead of being positioned intermediate the ends. Each jack 50, for example, is positioned between the adjacent ends 51, 51 of the individual lengths of curb, each of which has a slot in the end. A plate is received in each of the slots and provides a flexible joint between the curb sections and the jack on which it rests. This construction is shown more in detail in Figs. 14 and 15 in which each end of the curb is provided with a casting 52 providing the slot referred to. In the left hand slot, shown in Fig. 15, is fitted a casting or hinge member 53 the shape of which is evident from Fig. 14, and in the right hand slot there is provided another casting or hinge member 54, which members have circular enlargements or openings to receive a hinge pin 55. About the middle of the pin 55 is a third casting 56 which has an extension plate 57, shown in Fig. 15, bolted to the top plate 58 of the jack assembly so that the hinged structure rests on the jack and spring assembly. The clearances between the hinged members and the walls of the slot are sufficient to permit the sections to be raised with one end slightly in advance of the other, providing a gradual incline and also it permits the curb to follow the up and down undulations of a rolling road as well as to provide lateral clearance for right and left curves.

In some cases the power station is located in a suitable enclosure at the side of the road with the connecting pipe lines running to each of the several trenches in which the curbs and jacks are located. In other cases a separate power station or pumping unit is installed in each trench, as shown for example in Fig. 23 hereinafter described. The pumping units are provided with a remote control so that they may be operated together or independently from a distance. These controls may be time controls if desired, to operate the curbs automatically at certain times of the day.

Fig. 19 shows in perspective a modified arrangement for applying the lifting power. The motor driven compressor 60 develops the necessary power to move the plunger 61 horizontally in the concrete trough, thus tending to straighten the arms 62, 63 of the toggle member, the upper

one of which raises the plate 64 which supports the adjacent ends of the concrete curb 65. The spring arrangement 66 may be similar to that previously described. With this arrangement the plunger or piston operates horizontally instead of vertically, thus making it possible to install the equipment in the limited space provided by the trench or a slight enlargement thereof.

Various other mechanical arrangements may be used, whereby the piston, plunger or jack may be mounted in a comparatively limited space and its power made effective in an upwardly and downwardly direction. Where a cylinder and piston are employed the fluid pressure may be used, of course, to move the piston downwardly as well as upwardly, thus dispensing with some or all of the springs, if conditions permit.

In the constructions thus far described, the power is supplied by fluid under high pressure in excess of one thousand pounds per square inch and ample storage or ample pump capacity is required as the fluid pressure must be used in a short interval of time. For example, the curbs are raised in about ten to thirty seconds, depending on conditions. In order to avoid the difficulty of furnishing this large capacity in a limited space, I have provided, as in Fig. 20, a modified arrangement in which the power is stored in powerful springs which may be put under compression gradually over a long period of time.

The drawing is somewhat diagrammatic, showing a curb 67 which may be raised by a spring or springs 68. As shown, the spring is compressed between the end of the latch seat 69 and the plate 70, the latter being moved by the plunger 71 of a ram or jack. The lowermost position of the plate 70 is shown in dotted lines and the spring, although expanded somewhat, is under considerable compression and exerts a substantial minimum thrust in this position. As the plunger 71 moves upwardly, and after the curb has reached its upper position, the spring is compressed to its maximum amount, assuming the position shown in Fig. 21 in which the plate 70 is locked by the spring latches 72 to the lower rim of the latch seat 69.

During this upward movement the other springs 73 have been compressed and tend to lower the curb, which, however, remains in its uppermost position as long as the power continues to be applied to the jack. In order to lower the curb the power is released, whereupon the weight of the curb, aided by said springs, causes it to descend in the manner previously described. The plunger 71, as it descends, carries the latch seat 69 and the spring with it, in locked position.

When it is desired to raise the curb, the power is again applied and as the plunger 71 starts to lift, the latches are automatically tripped, whereupon the curb is raised rapidly by the expansion of the powerful spring 68. The plunger continues to move upwardly slowly under the pressure supplied by the system and thus the energy is again stored in the spring over a long interval of time.

The mechanism just described is shown in vertical position but it is preferably mounted in horizontal position in the space available in the trench and in such position, as shown diagrammatically in Fig. 22, may be applied to a series of toggle levers which move the curb vertically when the power is applied horizontally. In this figure the spring compression mechanism just described is shown as a whole at 75, including the spring 68.

The toggle mechanism 76 has its upper end engaging beneath the curb 77 and is provided with additional springs 78, 79, which correspond to the springs 73 in Fig. 20, i. e. when they expand they lower the curb.

Fig. 23 shows a curb construction in which the actuating mechanism is located within the curb itself. The curb 80 is elevated by jacks 81 in a manner similar to what has been described, the jack resting on a fixed foundation 82 in the trench. The springs 83 operate in the manner previously described, being mounted on rods some of which are anchored in the base of the trough. The motor driven compressor 84 is located in the curb and the supply pipe 85 extends therefrom to the jacks 81. 86 is the return tank. The curb is provided with hinged sections 87 to render the mechanism available.

When drivers of cars are approaching the portion of the road where the installation of the curbs begins and where it is desired to move part of the traffic over into the narrower of the two lanes, I may provide the equipment shown in Fig. 1 where the diagonal curb section 88 is raised from the roadway, from the end of the middle line of curbing to the end of one or the other of the outside movable curbs. Thus the traffic is directed into the narrower of the two highways and the traffic in the opposite direction is directed over to the side of the road.

Although the embodiment of the invention selected for illustration shows three adjustable curbs, it is obvious that a greater or less number may be used.

As the curbs rise and compress the springs, the limit of upward movement of the curb can be determined by the springs themselves. However, it is preferable in many cases to provide a positive stop, as for example a piston on the plunger or piston rod engaging the end of the cylinder.

Also, it is evident from the location of some of the fluid actuated plungers shown in the drawings that said plungers or piston rods may move either vertically, horizontally or in any other desired position and connected by suitable mechanism to the curb or barrier. Also, certain parts of the equipment described may obviously be used with or without other parts.

I claim:

1. In a highway construction, the combination with a pavement having a longitudinal slot therein, of jacks positioned in said slot at intervals, a vertically movable curb arranged in sections end to end near the top of said slot and means at the upper end of each jack connected to the adjacent ends of two of said sections, whereby each section is provided with two jacks to raise the same, depending members on said curb sections each supporting a compression spring near the lower end thereof, relatively fixed abutments for the upper ends of said springs and means for applying fluid pressure to said jacks to raise said curb sections and to compress said springs, whereby said curb sections may descend under the influence of said springs when said fluid pressure is released.

2. A highway construction as in claim 1, in which said depending members and said springs are arranged in groups with a spring on each side of each of said jacks.

3. Means for dividing highways into separate lanes comprising a concrete trough having vertical guard members imbedded in the side walls, a curb section fitting between said guard members, a plurality of fluid pressure jacks on which said

curb section is supported, supply pipes to each of said jacks to permit actuation of the same and raise said section, said curb having an H cross section with paving material in the upper channel flush with the top thereof, depending groups of rods secured to the transverse plate of said H section and having upturned lower ends to seat a vertical, helical spring, a stop plate for the upper end of each of said springs, and a holding rod for said plate anchored in the bottom of said trough whereby upward movement of said curb compresses said springs and insures subsequent downward movement of said curb when said fluid pressure is released.

4. A highway construction comprising a concrete lined trench, a curb length loosely fitted therein, a plurality of fluid pressure jacks seated in said trench and supporting said curb with its top normally flush with the side walls of said trench, said curb comprising vertical metal plates connected by a transverse plate, two pairs of depending rods secured to said transverse plate, each pair being spaced from the other, an anchoring rod between each pair of depending rods, a helical spring surrounding the three rods of each group and having its lower end supported by said depending rods and its upper end confined by said anchoring rod whereby upward movement of said curb compresses said springs and whereby release of the fluid pressure in said jacks initiates the downward movement of said curbs under their own weight, when retarded by ice and other obstructions.

5. A pavement construction comprising a concrete lined trench intermediate the sides of the roadway, a series of fluid pressure jacks mounted vertically on the bottom of said trench in uniformly spaced relationship, a vertically movable curb above said jacks, a seat adjacent the base of said jacks, a vertical support secured to the under side of said curb and resting on said seat to limit the downward movement thereof, said jacks each having a vertical support also engaging the under side of said curb to raise and support the same, and guide members in the sides of said trench to provide lateral movement of said curb in its up and down movement.

6. In a construction comprising a trench having means therein for raising and lowering a barrier to provide traffic lanes, a fluid pressure operated plunger, a compression spring having one end connected to said barrier and having the other end connected to said plunger to transmit its thrust to said barrier and raise the same, and to compress said spring against the resistance of said barrier when in its uppermost position, means for latching said spring in compressed position to store energy, an additional spring connected to said barrier and put under tension when the same is raised, whereby upon release of said fluid pressure said last mentioned spring lowers said barrier causing said first mentioned spring and plunger to return to initial position as a unit with said spring held in compressed condition, and means for unlatching said spring during the initial lifting movement of said plunger, whereby the expansion of said spring raises said barrier and whereby upon the re-application of fluid pressure to said plunger the necessary energy may be stored in said first mentioned spring at a slow rate so as to enable said barrier to be raised thereby subsequently, at a rapid rate.

7. In a highway construction, a trench substantially parallel to and between the sides of

the highway, and having side walls, a longitudinally arranged sectional curb fitting therein, means for raising and lowering said curb whereby it may project above the sides of said trench to separate said highway into independent lanes, or it may be lowered flush with the top of said trench, incandescent lamps within said curb sections and transparent members in the side walls thereof whereby when said curb is elevated it becomes visible at night, said curb sections being of hollow construction from end to end with electrical conductors extending therethrough, connected to said illuminating means and flexibly connected with the conductors of the adjacent section, whereby the circuit to said electrical illuminating means may be maintained when one section is raised or lowered somewhat in advance of the next section, said incandescent lamps being mounted in slideable carriages which may be inserted in or withdrawn from the curb through openings in the sides thereof.

8. In a paving construction, a concrete conduit having longitudinal reinforcing castings lining the open top thereof with lateral extensions imbedded in the side walls thereof, brackets also imbedded in said side walls, at spaced intervals below said open top and having vertical extensions thereon to provide wear resisting surfaces, a curb vertically adjustable in and out of the top of said conduit between said castings and positioned against lateral thrusts by said wear resisting surfaces, said curb having a lug on each side thereof positioned adjacent said vertical extensions to prevent longitudinal movement of said curb.

9. In a highway construction, the combination with a pavement having a longitudinal slot therein, of jacks positioned in said slot at intervals, a vertically movable curb arranged in sections end to end near the top of said slot, pivotal means at the upper end of each jack connected to the adjacent ends of two of said sections, whereby each section is provided with two jacks to raise the same, supply pipes to each of said jacks to permit actuation thereof where- 45

by, by supplying fluid pressure simultaneously to all of the jacks of a plurality of curb sections, said sections may be raised as a composite unit, followed by the raising of another composite unit, said pivotal means between the ends of said sections permitting progressive elevation of said curb as a whole.

10. In a highway construction, the combination with a pavement having a slot therein substantially parallel to and between the sides of the pavement, of jacks positioned in said slot at intervals, a vertically movable curb in said slot arranged in sections end to end with their upper surfaces substantially flush with said pavement, said sections being supported by said jacks, intercommunicating supply pipes to each of said jacks to supply fluid pressure thereto, to raise said sections simultaneously or in succession, whereby said highway is divided by said curb into two independent roadways of predetermined width when said curb is in elevated position, and consists of a single unobstructed roadway as wide as said combined independent roadways, when said curb is in lowered position.

11. In a highway construction, the combination with a pavement having a plurality of slots therein to divide the same into a number of individual roadways in excess of the number of slots, of jacks positioned in each of said slots at intervals, a vertically movable curb arranged in sections end to end in each of said slots and mounted on said jacks with the upper surfaces of said sections substantially flush with said pavement to provide a single composite roadway of a width equal to the combined widths of said individual roadways, supply pipes connected to a single source of pressure and to each of said jacks to supply fluid pressure thereto to raise said sections, whereby by elevating one curb and retaining the others in flush position, any one of several roadways of predetermined relative widths may be provided in proportion to the requirements of traffic flowing at different periods of time.

OTTO K. JELINEK.
